George A. Lehmann, St. Louis, and William E.
Gundelfinger, House Springs, Mo.

Application March 26, 1952, Serial No. 19,054

Term of patent 14 years

(Cl. D22—2)

To all whom it may concern:

Be it known that we, George A. Lehmann and William E. Gundelfinger, both citizens of the United States, residing respectively in St. Louis and House Springs, Jefferson County, Missouri, have invented a new, original, and ornamental Design for a Can Opener, of which the following is a specification, reference being had to the accompanying drawing, forming a part thereof.

In the drawing:

Fig. 1 is a top plan view of a can opener, showing our new design;

Fig. 2 is a side elevational view thereof;

Fig. 3 is a front end view thereof;

Fig. 4 is an elevational view of the opposite side thereof, and

Fig. 5 is a bottom plan view thereof.

I claim:

The ornamental design for a can opener, substantially as shown.

GEORGE A. LEHMANN.
WILLIAM E. GUNDELINGER.
